UNITED STATES PATENT OFFICE.

THOMAS HOLAHAN, OF ROCHESTER, NEW YORK.

TROLLEY-CATCHER.

SPECIFICATION forming part of Letters Patent No. 577,921, dated March 2, 1897.

Application filed July 11, 1896. Serial No. 598,889. (No model.)

To all whom it may concern:

Be it known that I, THOMAS HOLAHAN, of Rochester, in the county of Monroe and State of New York, have invented a certain new and useful Improvement in Trolley-Catchers; and I do hereby declare that the following is a full, clear, and exact description of the same, reference being had to the drawings accompanying this application.

10 My improvement relates to a device for automatically drawing down the trolley-arm in case the trolley disconnects from the conducting-wire, thereby preventing it from striking the guy-wires and other connections.

15 The invention consists in the combination and arrangement of parts hereinafter described and claimed.

In the drawings, Figure 1 is a sectional elevation of the apparatus. Fig. 2 is a similar view at right angles to Fig. 1. Fig. 3 is an enlarged section of the top of the casing containing the working parts. Fig. 4 is a vertical cross-section of one side of the bottom of the casing, showing one of the spring cases and rollers for winding the metallic straps. Fig. 5 is an enlarged vertical section of the air-cylinder.

A indicates the trolley-arm.

B is a case or boxing for containing the operating parts. This case is attached at any suitable place on the end of the car to operate with the trolley-cord.

C is an air-cylinder fixed in the bottom of the case, its bottom being closed and its top open and made flaring to receive the piston.

D is a slide moving up and down in ways *a a* of the case. To this slide is attached a rod *b*, having at its lower end a piston *E*, which enters the cylinder *C* when forced down.

40 F F are two thin metallic winding-straps similar to those used in spring sash-balances, one end of each being attached to the slide *D*, the other end passing through the side of the casing and winding on a spring-actuated roller *c*, whose tendency is always to draw the slide down. A single strap instead of two may be used, if desired.

45 *d* is a spring-hook attached inside the casing at the top, and *f* a reverse hook attached to the slide *D*, which two hooks engage together when the slide is raised. When the hooks are disengaged, the slide is drawn down-

ward by the winding-straps and the piston *E* then enters the air-cylinder *C* and compresses the air therein. The air under compression 55 escapes through a small orifice *g* in the cap *h* of the cylinder. This orifice is covered more or less by screwing the cap *h* up or down, by which means the escape of air is graded to the work to be done. 60

G is the ordinary cord by which the trolley is operated. H and I are two other cords, one being attached to the slide *D* and extending up through a bushing in the top of the case, the other being attached to a pivoted latch 65 *k*, which bears against a stem *l* of the spring-hook *d*. The upper ends of these two cords are attached to a snap-hook *m*, which in turn is hooked into a ring hung to the trolley-cord. By this means the cords can be disconnected 70 to swing the arm around to the opposite end of the car. One of these attachments is used at each end of the car, and there is no difficulty in connection and disconnection of the parts. 75

In use the slide *D* is drawn up to the top of the case *B*, when the two hooks engage and hold the slide elevated. The cords are then connected with the trolley-cord. If the trolley-arm becomes disconnected from the conducting-wire and springs upward, it draws on cord *I*, raises the latch *k*, draws the spring-hook *d* back, and disengages the two hooks. The winding-straps *F F* draw the slide down, also the cord *H* and the trolley-arm, so that 80 the trolley is drawn back below the main wire. When the slide approaches the bottom, the piston *E* enters the open-ended air-cylinder *C* and compresses the air therein, which gradually escapes through the hole *g* and eases 85 the shock. The compressed air forms an air spring and cushion at the end of the stroke. At the beginning of the stroke the movement is quick to draw the trolley down before it can strike any obstruction. By the use of 90 95 this apparatus the action is automatic and requires no attention of the conductor.

The trolley-arm is constructed with an outer short section *A'*, which is hinged at *p* to the main arm *A*, by which it can turn upward 100 independent of the arm. A spring *r*, connected with the two parts, tends to turn it upward. In case the trolley is detached from the wire this short section is drawn up before

the main arm is. The cord H is somewhat slack and the cord I straight, which enables this to be done. By drawing up the section in advance the apparatus is quicker in operation than if the whole arm is drawn up, and the arm is drawn back quicker below the wire, thereby freeing it before it can come in contact with any obstruction.

Having described my invention, what I claim as new, and desire to secure by Letters Patent, is—

1. In a trolley-catcher, the combination of an open-ended air-cylinder provided with a discharge-orifice; a slide movable forward and back; a piston attached to the slide adapted to enter the open end of the cylinder; a connection attached to the slide; a spring-roller on which the connection winds; a spring-hook at the top of the casing and a corresponding hook on the slide, which two hooks engage together when the slide is raised; a latch for operating the spring-hook; a cord

connecting the slide with the trolley-arm; and another cord connecting the latch with the trolley-arm, the whole arranged to operate in 25 the manner and for the purpose specified.

2. The combination, with the trolley-arm, of a section hinged thereto to turn upward; a spring for forcing the same upward; and two cords connected at one end to a pendant of 30 the hinged section, and at the other end, one with a winding apparatus for drawing the trolley down, and the other with a disengaging device that operates the locking devices of the winding apparatus, as herein shown 35 and described.

In witness whereof I have hereunto signed my name in the presence of two subscribing witnesses.

THOMAS HOLAHAN.
